UNITED STATES PATENT OFFICE.

HERBERT M. ELDRIDGE AND REUBEN C. ELDRIDGE, OF NIAGARA,
CANADA.

DESIGN FOR A STALL-FIXTURE.

SPECIFICATION forming part of Design No. 29,071, dated July 19, 1898.

Application filed June 23, 1898. Serial No. 684,303. Term of patent 7 years.

To all whom it may concern:

Be it known that we, HERBERT M. ELDRIDGE, a citizen of the United States, and REUBEN C. ELDRIDGE, a subject of the Queen of Great Britain, both residing at Niagara Falls, in the Province of Ontario, Dominion of Canada, have invented and produced a new and original Design for Stall-Fixtures, of which the following is a specification, reference being had to the accompanying drawings, forming a part thereof.

This design relates to the configuration of the upright rods or fixtures which are employed in cow or other animal stalls for the attachment of the free end of the cow tie or chain.

In the accompanying drawings, which illustrate our new design, Figure 1 is a perspective view of a stall-fixture embodying the design. Fig. 2 is a transverse section in line 22, Fig. 1.

Like letters of reference refer to like parts in both figures.

The distinctive feature of our design consists of an upright bar which is trough-shaped or U-shaped in cross-section and flat offset ears or flanges arranged at the ends of the bar.

A is the body or upright bar of the stall-fixture, which is U-shaped in cross-section, as shown in the drawings, the rounded or convex side of the bar facing outwardly and its vertical edges facing inwardly.

B are the flat upright ears or flanges, which are arranged at the ends of the bar A and offset inwardly beyond the same. These ears are wider than the bar A and their inner portions taper toward the bar. The flanges which form the sides of the channeled bar gradually become narrower adjacent to the ears.

c represents perforations in the ears.

What we claim is—

The design for a stall-fixture substantially as herein shown and described.

Witness our hands this 14th day of May, 1898.

HERBERT M. ELDRIDGE.
REUBEN C. ELDRIDGE.
